DESIGN FOR A DRINKING GLASS

Alexander F. Richards, Mayport, Pa.

Application September 3, 1943, Serial No. 111,059

Term of patent 14 years

To all whom it may concern:

Be it known that I, Alexander F. Richards, a citizen of the Dominion of Canada, residing at Mayport, in the county of Armstrong, and State of Pennsylvania, have invented a new, original, and ornamental Design for Drinking Glasses, of which the following is a specification, reference being had to the accompanying drawing, forming a part thereof.

I claim:

The ornamental design for a drinking glass, as shown.

ALEXANDER F. RICHARDS.
